(57) **CLAIM**

The new ornamental design for a water purifying filter, as shown and described.

DESCRIPTION

FIG. 1 is a perspective view of the water purifying filter, showing our new design;

FIG. 2 is a front view of the water purifying filter thereof; FIG. 3 is a rear view of the water purifying filter thereof; FIG. 4 is a left side view of the water purifying filter thereof; FIG. 5 is a right side view of the water purifying filter thereof;

FIG. 6 is a top view of the water purifying filter thereof; and, FIG. 7 is a bottom view thereof.

FIG. 1A is a partially enlarged view of FIG. 1. As described in FIG. 1A, the head of the water purifying filter is shaped as circular.

The details shown in broken lines are for illustrative purposes only and form no part of the claimed design.
